HARRISON M. TURNER, OF LOUISVILLE, KENTUCKY, ASSIGNOR OF ONE-HALF TO JOSIAH B. GATHRIGHT, OF LOUISVILLE, KENTUCKY.

CAR-CLEANING APPARATUS.

No. 894,919.

Specification of Letters Patent.

Patented Aug. 4, 1908.

Application filed September 29, 1902, Serial No. 125,329. Renewed December 30, 1907. Serial No. 408,695.

To all whom it may concern:

Be it known that I, HARRISON M. TURNER, a citizen of the United States, residing at Louisville, in the county of Jefferson and State of Kentucky, have invented certain new and useful Improvements in Car-Cleaning Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention presents an apparatus operative to direct a stream or streams of fluid or fluids against the exterior of a railway or other car for the purpose of cleansing the same between trips, or for cooling the same 20 in summer, and by the use of which the employment of the hand labor now used in the cleansing of the exteriors of railway cars may be avoided and the operating expenses of railroads thus materially reduced.

25 Among the objects of the present invention are, first, to provide a cleansing or cooling device for the exteriors of railway cars etc., the operation of which will be automatically controlled by the cars to be cleansed or 30 cooled: second, to provide means by which the closing of the valve which controls the supply of water to the discharge pipes will be automatically retarded; third, to provide means which will effectually cleanse and cool 35 the ends as well as the sides of railway cars: fourth, to provide means for cleansing the exteriors of railway cars which will render unnecessary the use of brushes and will thereby obviate the marring of the paint due to 40 the employment of brushes: fifth, to provide, for washing or cooling the exteriors of railway cars, an apparatus having means by which the sizes of the outlet openings may be adjusted whenever desirable or necessary: 45 sixth, to provide an apparatus for washing or cooling railway cars which will be adapted to be operated automatically by a car to be cleansed or cooled and is also adapted to be temporarily unaffected by a passing car: 50 seventh, to provide an apparatus for cleansing and cooling cars which may be adjusted at will to be operated automatically by a car approaching from one direction only, or by a

car without regard to the direction of approach thereof, or to be unaffected by a passing car.

To these several ends the invention, as hereinafter fully set forth and definitely pointed out in the subjoined claims consists, essentially, first, in the combination with means through which a stream or streams of fluid may be supplied to the surface to be cleansed or cooled, of pivoted means controlled by the car to be washed or cooled for automatically controlling the supply of fluid to said surface: second, in the combination with fluid-supply means, a valve controlling the supply thereof and a device actuated by a passing car to open the valve when the car approaches the apparatus and to hold the valve open while the car is in position to be cleansed or cooled, of means for automatically closing said valve when the car has passed out of engagement with said device, said closing means being such that the closure may be effected at a speed which will render it unnecessary to reopen the valve for each car of the passing train being washed or cooled: third, in a novel arrangement of water exits by which they are caused to direct their streams respectively forward and rearward slantingly toward the car: fourth, (a) in a novel construction of water exits by which the water is directed forcibly against the side of a car in a solid sheet reaching approximately from the top to the bottom of the wall thereof; (b) in the combination with means for forcibly directing a stream or streams of water against the side of a railway car to be cleansed, of means by which a stream or streams of air may be directed against said side to blow the dust etc., therefrom in advance of the supply of water thereto: fifth, in a discharge pipe for car-cleansing apparatus formed with a longitudinal discharge opening and having means operative to draw and hold the side walls of said opening nearer to or further from each other to thereby adjust the width of said opening: sixth, in the combination with water-conducting means of car cleansing apparatus, including a valve operative to permit or cut-off the passage of water, of an adjustably-supported device connected with said valve to operate the same, said device being adapted to be ad-

justed into the path of a passing car to be operated thereby or out of the path of said car so as to be unaffected thereby: seventh, in the combination with water-conducting means of car-cleansing apparatus, including 5 a valve operative to permit or cut off the passage of water, of a device mounted to be adjustable into the path of a passing car so as to be automatically operated to open the valve, and to be adjusted and held out of 10 said path when it is not desired to operate it automatically, and means for locking it when desired against being forced into the latter position by the engagement with it of a car traveling in the direction in which it 15 moves to said latter position.

The invention also consists in certain further novel combinations of parts embodied therein: and in novel details entering into 20 and constituting the preferred construction thereof, substantially as hereinafter described and particularly pointed out in the subjoined claims.

In the accompanying drawings illustrating 25 desirable means for carrying into effect the several purposes of the invention, Figure 1 is an end view of the car cooling and cleansing apparatus, showing a car being cooled or cleansed thereby, said view also illustrating in dotted lines the position of parts when 30 the apparatus is not in use. Fig. 2 is a front view of the part of the apparatus located at one side of the track. Fig. 3 is a plan view of one side of the apparatus, showing adjustments of the head in dotted lines. Fig. 35 4 is a view looking at one end of Fig. 3, showing the head locked so as to operate the valve by the engagement with it of a car traveling in either direction. Fig. 5 is a detail view 40 of the standpipe, showing the ends thereof broken away to disclose the valve and valve-retarding means therein. Fig. 6 is a detail view of a means by which the width of the exit opening in the discharge pipe may be 45 adjusted. Fig. 7 is a sectional view of one end of a branch pipe and its depending fluid discharge pipes, provided with a valve for controlling the supply of compressed air thereto. Fig. 8 is a side elevation of a part of a modified 50 construction. Fig. 9 is a plan view of said modified construction. Fig. 10 is a side view showing a modified construction of dusting means. Fig. 11 is a view showing a different construction of means for slowly 55 bleeding the piston chamber of the valve-retarding means, and Fig. 12 is a detail view of a portion of one of the discharge pipes, clearly showing its construction by which the diameter of its discharge opening may be 60 adjusted.

In the present invention the cars are cleaned by means which are respectively, adapted to remove the loose dust and adherent dirt from the surface of the car. These means, as herein embodied, constitute dust-

ing and washing instrumentalities which are arranged in operative succession, in the order named, along the length of the car. Thus, in the cleansing of the car, the loose dust is removed from the surface immediately prior to the washing thereof. The dusting instrumentality may in the broader aspects of the invention be of any suitable character, but it preferably contemplates the use of compressed air, or other dry fluid under pressure, 70 adapted to blow the dust from the surface without marring the latter. The washing instrumentality obviously contemplates the use of water, or other suitable washing fluid, and it is preferred so to construct the same as 75 to avoid the necessity of the use of brushes in the washing operation. 80

The operation of the dusting and washing instrumentalities is effected by a common actuating means which, as herein embodied, 85 is operated by or under the control of the car to be cleansed. This actuating means has a pivoted lever 19 which is provided at one end with a head 9 which projects into the path of the car to be cleansed and is engaged and 90 pushed back by the latter to turn the lever pivotally, and said lever is so connected with the valve 6 of the washing instrumentality as to move the same from its seat when the lever is thus turned. When the dusting instrumentality discharges adusting fluid, it is provided with a valve 40 similarly having suitable means by which it is moved from its seat when the lever is turned pivotally by the car to be 95 cleansed. The head on the lever is preferably rotatable, whereby its liability to scratch the surface of the car is reduced to a minimum. Moreover, when the dusting instrumentality employs a rotative brush, such a head has an additional function, for it then becomes practicable to utilize it to communicate motion 100 directly to said brush, as hereinafter clearly set forth. 105

Having thus in a general way set forth some of the important features of the invention, I will proceed more fully to describe the construction and operation of the same, as follows:—

The same numerals of reference designate 110 the same parts in the several figures. 115 A pipe or pipes 1 constructed and arranged to direct the stream of cleansing and cooling fluid against the exterior of a car is employed in the system. The purpose of this invention will best be subserved by the employment of a series or battery of said pipes 1 at each side of a track along which passes the car to be cleansed or cooled, so that a plurality of streams of the fluid will be directed simultaneously against each side of the car. 120 It is also greatly preferred that the outlets from the pipes be arranged to cause the fluid to issue therefrom in a direction inclined to the length of the car to be washed, and with one portion of each series slanting forward 125 130

and the other rearward toward the car, whereby the ends as well as the sides of the car will be reached by the cleansing and cooling fluid, as clearly indicated by the dotted lines in Fig. 3. The distance between the two batteries of pipes is so adjusted as to prevent the streams of fluid issuing therefrom from interfering with each other between the cars. By directing the streams aslant to the surface to be washed thereby the latter is more effectually cleansed than it would be if the streams were directed against the same in a direction at right angles therewith.

A most important advantage will be gained by employing as the outlet of each pipe 1, a continuous slot 2 extending longitudinally of the pipe and approximately as long as the height of the car-body to be cleansed, whereby the stream will issue in a continuous sheet (instead of in a series of jets) which bears such relation to said body as forcibly to strike every portion of the same from top to bottom equally. This construction makes it practical to rely upon water under pressure as the principal or sole means of cleansing the car and dispenses with the necessity of the use of brushes as the principal cleansing means.

It is within the scope of the invention to employ a pipe or system of pipes on one side only of the track or car and to supply it or them in any suitable way, and when a pipe or series of pipes are employed on each side of the car or track they may be supplied independently of each other, be of the same or different construction and have the same or different valve-operating means. But it is greatly preferred as above indicated to employ a system of pipes at each side of the car or track, supply both from a means common thereto and control the supply for both by a common valve and valve-actuating means.

A suitable water supplying means includes a standpipe 3 connected with a suitable source of supply through the pipe 4. The battery of discharge pipes on one side of the car or track preferably depend from branch pipes 11 connected with the upper end of the standpipe, while the battery of pipes on the other side may rise from corresponding branch pipes 11 which are connected, for example by the pipe 5 extending beneath the road bed, with the lower end of said standpipe. Arranged in the standpipe 3, below the junction of the pipe 5 therewith, there is a valve 6 which controls the supply of water to both batteries of discharge pipes. This valve 6 is provided with a stem 7 and is moved to and from its seat 8 by a means the operation of which is controlled automatically by the passing car to be cleansed or cooled. Any means for this purpose which is so connected with the valve or its stem as to operate the same and which is arranged to be

operated automatically by a passing car to be cleansed or cooled, is within the scope of the invention. The means preferred for the purpose includes a roller, which is well adapted to serve the function with a minimum of friction, arranged to be operated by the body of the car. Suitable means are also provided for automatically returning the valve 6 and its operating mechanism to their original positions, upon the passing of the car or train, so as to automatically shut off the discharge of water and leave the parts in position to be operated by another train to be cleansed or cooled.

Two different constructions of valve-operating means (the differences being in the connections between the head and valve-stem) are shown in the accompanying drawings, as examples. One form, in which the head is designated by the numeral 9, is designed for use in situations where there is ample space to permit the standpipe 3 to be arranged sufficiently distant from the batteries of pipes 1 on its side of the car to enable a lateral connecting pipe 10 to be employed between said standpipe and the branch pipes 11. In this construction a bodily-movable rod 12 is lowered to depress the valve 6 from its seat, said rod suitably engaging the valve-stem 7 and being supported and connected with the head 9 so as to have said bodily movement imparted to it in one direction when said head is struck by a passing car. A most suitable means for connecting it with said stem consists of a slot 13 formed longitudinally in it and receiving a pin 14 projecting laterally from said stem, whereby when said rod 12 is lowered in the arc of a circle it will move relatively to and depress said valve stem. Preferably there are two of these rods 12 employed, one at each side of the upper end of said stem, whereby tendency to wobbling or lateral movement of the stem and diversion of the valve 6 from a straight line in its movements is avoided. A most suitable means for operating said rods 12 includes levers 15 the upper ends of which are connected by said rods (which are pivoted thereto as shown at 16) and the lower ends of which are pivoted between lips or flanges 17 which project from clamping members 18 suitably secured to the upper end of the standpipe. The motion which operates the rods 12 is communicated to one of said levers 15 and the two levers (15) combine with each other and with said rods 12 to give the latter rods their proper movement. For transmitting motion from the head 9 to the lever 15 a most suitable means embraces a lever 19 which is fulcrumed at 20 between its ends 125 and has one of its ends connected with said lever 15 by a link 21 while its other end carries said head 9. This lever is shown as arranged above one of the branch pipes 11 and as extending from beyond the free end of the 130

latter to the connecting pipe 10, and the link 21 extends over said connecting pipe to the lever 15 from a projection 22 which rises from said lever.

5 The operation of the parts thus far described is as follows: Normally, the valve 6 is on its seat 8, its stem is elevated, the levers 15 are approximately vertical, the rods 12 are in their highest position, the head 9 is located over the plane of the tracks or in position to be operated by a car and the lever 19 and link 21 occupy their corresponding positions. The first car of a train, approaching the cleansing means in the direction of the 10 arrow *a*, Fig. 3, strikes the head 9 and moves it bodily outward, thus causing the lever 19 to turn on its pivot 20, in the direction of the arrow *b*, to the position shown in full lines in Fig. 3, thereby depressing the valve and 15 causing the car to be washed by the water issuing in sheets from the pipes 1. To return the several parts automatically to their original positions, a weight 23, suitably connected with the lever 19 by means of a cord or 20 chain 24 and pulley, 25, may be employed.

With the construction thus far described the supply to the discharge pipes will be closed immediately a car passes out of engagement with the head 9, and when a train 30 of cars is to be washed or cooled must be opened by each car thereof. To obviate this, any suitable means are provided by which the valve is closed slowly upon the passing of a car out of engagement with the head. 35 The means preferred embrace a water chamber 26, located in the upper end of the standpipe 3 and divided from the main chamber in said pipe by a floor or diaphragm 27, said chamber 26 having provision for slow bleeding. A space may be provided around the 40 stem 7 and in the floor 27, through which said chamber 26 has communication with the standpipe, and the portion of said chamber above the piston 28 has communication with 45 the portion thereof below the piston through spaces which may be provided for said purpose between the perimeter of the piston and the wall of said chamber. Thus, when the valve 6 is open water will flow from the 50 standpipe into the chamber 26 and above the piston, and as the piston ascends the water above the same will slowly return to the standpipe. In Fig. 11, a different means for the same purpose is shown, wherein the piston 28* has a flap valve 29* which will permit water to flow into the portion of the chamber above said piston, and said portion has a cock or valve 30* through which the water is slowly forced by the upward 55 movement of the piston. By either of these means the raising of the valve 6 to its seat is resisted by the pressure of the water above said piston and the closing of the valve is materially retarded. The operation of the 60 returning means preferably is such that 65

there is little appreciable closing movement, if any, of the valve during the time between the disengagement of one car of a train from the head 9 and the engagement of said head with the next car of the train. Thus, the 70 valve will be held open until after the entire train has passed, which fact, together with the aforementioned aslant arrangement of the discharge openings, assures that the entire train, including the ends of the cars 75 shall be effectually washed. This means also avoids liability of damage to the pipes which may occur from back pressure when the valve is closed suddenly.

In the modified construction, shown in 80 Figs. 8 and 9, the branch pipes, designated 11^a which carry the discharge pipes 1^a are connected directly with the standpipe 3^a, the pipes 10 of the other construction being dispensed with, and said discharge pipes project upward from said branch pipes. The connecting means between the valve stem 7^a and the head 9^a is changed to suit the changed arrangement of pipes. Said head 9^a is carried by one end of a lever 19^a the 90 fulcrum 20^a of which is at its other end. Between its fulcrum 20^a and power end (which latter is bent upward as shown at 22^a) this lever is provided with a link 21^a which connects it with one arm 15^a of a bell-crank 95 lever, the other arm 12^a of which bell-crank lever engages the upper end of the valve-stem 7^a or a projection therefrom. Thus, when a car strikes the perimeter of the head 9^a and pushes the same back in the direction 100 of the arrow it correspondingly forces back the lever 19^a, which thereby pulls upon the link 21^a and arm 15^a and causes the arm 12^a to press upon and lower the valve stem. A 105 spring 23^a encircling the upper end of said valve stem operates automatically to return the parts to their original positions.

To give elasticity to the parts and afford maximum facility for the flushing of the pipes to remove sediment and dirt therefrom, one end of each discharge pipe is left free and is normally closed by a cap 30 removably applied thereto. Suitable transverse slots 31 are formed in each discharge pipe or the pipe is otherwise so constructed 110 as to be expansible and contractible as to its diameter, and applied around each pipe is a clamp 32 or other suitable means operative to contract the diameter of said pipe or to permit the same to expand, whereby the 115 width of the discharge slot 2 therein is adjustable.

A useful adjunct to water in the effective cleansing of the car, comprises means for removing the loose dust and dirt in advance of 120 the application of the water to said car. Any means for this purpose is considered to be within the purview of broadest claims hereinafter presented which include dust-removing means broadly as an element. 125

Two means are shown in one of which (see Fig. 10) a dusting brush 38^a is mounted to rotate adjacent to the rotative head 9 and is rotated by frictional contact with the latter 5 when the latter is rotated by its engagement with the car. The preferred means, however, contemplates the use of air or other dry fluid under pressure expelled against the side of the car body and blowing the loose dust 10 or dirt therefrom. Preferably the discharge pipes 35 for the compressed air are similar to those hereinabove described for the water, and they preferably are connected with the same branch pipes 11 or 11^a through which 15 said water-discharge pipes are supplied. When said preferred construction is employed, a wall or plug 36 may be located at a suitable place in the branch pipe to divide it into two chambers having no communication 20 with each other, one 37 (Fig. 7) for the water supplied to said water-discharge pipes 1 and the other, 38, for the air supplied to the air-discharge pipes 35. The plug or wall 36 may be mounted to be adjustable within 25 the branch pipe so as to cut off the water at any point to give the desired number of air pipes in the system. In Fig. 7 it is shown as adjusted to cause the air to be discharged through two pipes at the end of the branch 30 pipe 11. In Fig. 2 it is indicated as adjusted for the use of only one air-pipe at the end of said branch pipe. An ordinary air nipple 39, mounted on said pipe 11 and connected with a suitable source of air under pressure 35 (not shown) may be employed to supply air to said chamber 38 and discharge pipe or pipes 35. It will be advisable to cut off the supply of air to said chamber 38 at the same time that the supply of water to the chamber 40 37 is cut off by the closing of the valve 6 and to open the supply to the chamber 38 when the water is turned on. Any suitable means for the purpose is within the scope of the invention. An example of means which may 45 be employed is shown in the drawings, said means consisting of an air-valve 40 located adjacent to the nipple 39 and provided with a spring 41 for pressing it to its seat, said valve being moved from its seat automatically by the engagement with its stem 42 of a wedge-shaped block 43 which is carried by the lever 19, so that when said lever is moved 50 to open the water-supply valve 6 it will carry said block with it and simultaneously 55 open the air-supply valve, and when said lever is moved to close said water-supply valve the narrower portion of the block will be brought opposite the stem 42 of the air-supply valve and the spring of the latter will 60 be permitted to force said air-supply valve to its seat.

It may sometimes be desirable to render the device temporarily inoperative by a passing car, which is preferably accomplished by 65 adjusting the head 9 out of the path of said

car. To this end said head is pivoted on one end of a lever 44 the other end of which is pivoted, at 45, to the free end of an arm 46 projecting from the free end of the lever 19. Normally the lever 44 underlies the arm 46 throughout its length, but it can be adjusted upon its pivot 45 to thereby carry the head out of the path of a passing car, as shown in dotted lines in Fig. 3. To lock it in the latter position there may be employed an axially movable bolt 47 having its ends bent in different directions one, 48 to engage a perforation 49 in said head and the other, 50, to attach an operating cord 51 to. A weight 52 will serve automatically to turn the bolt axially to its normal position when its end 48 is disengaged from said head, and a spring 53 will automatically return and hold said lever 44 and head in their said normal positions. Obviously, with the construction thus far 80 described, a car approaching the device from the direction of the arrow *c*, when the parts are in their positions with the head in the path of said car, will press upon said head and turn it with its lever 44 outward on the pivot 45, relatively to the lever 19, without moving the latter and hence without opening the valve 6. Thus said car will not be washed or cooled. But if it is desired automatically to wash or cool cars approaching from either 95 direction, the same may be accomplished by adjusting the bolt-end 48 downward across the path of the lever 44, thus locking the parts together so that the lever 19 will partake of the outward movement of the head 100 when the latter is struck by a passing car approaching in the direction of the arrow *c* as well as to partake of the outward movement of the head when the latter is struck by a car 105 approaching from the direction of the arrow *a*.

Having thus described the invention what is believed to be new and what is therefore claimed, is:—

1. In a car cleaning apparatus, means for removing loose dust and means for removing the adherent dirt, arranged in operative succession along the length of the car, a pivoted operating lever for said means, adapted to be moved in one direction by the car to be 110 cleaned, and means for moving said lever in the other direction.
2. An apparatus for cleaning the exterior of a car, comprising a dusting means and a washing means arranged for successive operation on said exterior, and an operating means for the dusting and washing means having connection with both of the same.
3. An apparatus for cleaning the exterior of a car, comprising a dusting means and a 125 washing means, adapted to operate on said exterior one in advance of the other, and an operating means for the dusting means and washing means, having connection with both of the same provided with an element in the 130

path of the car to be cleaned, whereby it is operated by said car.

4. An apparatus for cleaning the exterior of a car, comprising a dusting means, a washing means, and a common operating lever for said means.

5. An apparatus for cleaning the exterior of a car, comprising a dusting means, a washing means, and a common operating lever for said means, provided with an element in the path of the car to be cleaned, whereby it is operated by said car.

6. An apparatus for cleaning the exterior of a car, comprising means through which a dusting fluid and means through which a washing fluid are discharged against the exterior of the car, the former adapted to remove the loose dust preliminarily to the action of the other, and means for controlling the discharge of said fluids, having a common actuating means, adapted to be operated by the car to be cleaned.

7. An apparatus for cleaning the exterior of a car, comprising a pipe divided into separate chambers, means for conducting a washing fluid under pressure to one of said chambers, means through which a dusting fluid is supplied to the other of said chambers, said chambers having means for the discharge of the washing and dusting fluids toward the car to be cleaned thereby, valves for controlling the fluids and an operating means connected with both of said valves.

8. An apparatus for cleaning the exterior of a car, comprising a pipe divided into separate chambers, means for conducting a washing fluid to one of said chambers, means through which a dusting fluid is supplied to the other of said chambers, said chambers having means for discharging the washing and dusting fluids separately toward the car to be cleaned thereby, valves controlling the fluids, and operating means connected with both of said valves and having an element in the path of the car to be cleaned, whereby it is operated by said car.

9. An apparatus for cleaning the exterior of a car, comprising a dusting means and a washing means, adapted to operate one in advance of the other on said exterior, said washing means having means through which a washing fluid is discharged against the exterior of the car and a valve controlling the discharge of such fluid, and an actuating lever having means whereby it operates said valve and dusting means.

10. An apparatus for cleaning the exterior of a car, comprising a dusting means and a washing means, adapted to operate one in advance of the other on said exterior, said washing means having means through which a washing fluid is discharged against the exterior of the car and a valve controlling the discharge of such fluid, and an actuating lever provided with an element in the path of

the car to be cleaned so as to be operated thereby, said lever also having means whereby it operates said valve and dusting means.

11. An apparatus for cleaning the exterior of a car, comprising means through which a dusting fluid and means through which a washing fluid are discharged against the exterior of the car, the former adapted to remove the loose dust preliminarily to the action of the other, and an operating lever for controlling said means.

12. An apparatus for cleaning the exterior of a car, comprising means through which a dusting fluid and means through which a washing fluid are discharged against the exterior of the car, the former adapted to remove the loose dust preliminarily to the action of the other, each of said means having a valve, and an actuating lever having connection with said valves and adapted to be operated by the car to be cleaned.

13. In an apparatus for cleaning the exterior of a car, the combination with a valved fluid-conducting means having a discharge aperture directed toward the car, and an actuating means for the valve of said conducting means, having a lever arranged in the path of said car and operated thereby, and means for connecting the lever with the valve of the fluid-connecting means.

14. In an apparatus for cleansing or cooling the exteriors of railway cars, the combination with fluid-conducting means having a discharge pipe with an outlet arranged to discharge the fluid against the exterior of the car, and a valve for controlling the supply of fluid to said pipe, of means for operating said valve comprising a pivoted lever, connections between said lever and valve whereby the latter is opened when the lever is turned pivotally and means supported by said lever and arranged in the path of the car to be cleansed or cooled so as to be engaged by said car to turn the lever pivotally and thereby open said valve automatically.

15. In an apparatus for cleansing or cooling the exteriors of railway cars, the combination with fluid-conducting means having an outlet arranged to discharge the fluid against the exterior of the car to be cleansed or cooled, and also having a valve for controlling the supply of fluid to said outlet, of valve-operating means arranged to be operated by the car to be cleansed or cooled, comprising a pivoted lever supported by the fluid-conducting means and connected with said valve and a car contacting means supported by said lever.

16. In an apparatus for cleansing or cooling the exteriors of cars, the combination with fluid conducting means, having a discharge outlet and a valve for controlling the supply of fluid to said outlet, said valve having a stem, of a pivoted lever, connections between said lever and valve-stem for trans-

- mitting bodily movement to the latter from pivotal movement of the former, and a head carried by said lever and arranged to be operated by the car to be cleansed or cooled.
- 5 17. In an apparatus for cleansing or cooling the exteriors of cars, the combination with fluid conducting means, having a discharge outlet and a valve for controlling the supply of fluid to said outlet, said valve having a stem, of means for operating said valve including a bodily-movable rod engaged with said stem, pivoted levers, a connection for said levers, said connection being connected with said rod and means connected with one 15 of said levers for operating the same to thereby raise or lower said rod.
18. In an apparatus for cleansing or cooling the exteriors of cars, the combination with fluid conducting means, having a discharge outlet and a valve for controlling the supply of fluid to said outlet, said valve having a stem, of means for operating said valve, including a bodily-movable rod engaged with said stem, pivoted levers connected 25 with said rod, and supporting the same, a pivoted lever and a link connecting the latter lever with one of said supporting levers.
19. In an apparatus for cleansing or cooling the exteriors of cars, the combination with fluid conducting means having a discharge outlet and a valve for controlling the supply of fluid to said outlet, said valve having a stem, of means for operating said valve, including a bodily-movable rod engaged 35 with said stem, pivoted levers connected with said rod and supporting the same, a pivoted lever having a head in the path of the car to be cleansed and a link connecting the latter lever with one of said supporting levers.
- 40 20. In an apparatus for cleaning or cooling the exteriors of cars, the combination with a conducting means for the cleaning or cooling fluid, having a discharge outlet and a valve for controlling the supply of fluid to 45 said outlet, said valve having a stem, of an operating means for the valve comprising an actuating lever, devices movable relatively to the valve stem and engaging the stem, movable supporting means for said devices 50 and a connection between said lever and supporting means.
21. In an apparatus for cleaning or cooling the exteriors of cars, the combination with conducting means for the cleaning or 55 cooling fluid, having a discharge outlet and a valve for controlling the supply of fluid to said outlet, said valve having a stem, of an operating means for the valve, comprising an actuating lever having a car-contacting 60 device adapted to be operated by the car and to actuate said lever, devices movable relatively to the valve stem and engaging the stem, movable supporting means for said devices and a connection between said lever 65 and supporting means.
22. In an apparatus for cleaning or cooling the exterior of a car, a valved fluid conducting means, having a chamber and means for the discharge of the fluid, a piston mounted in said chamber and connected with the valve of the fluid conducting means, said chamber having means by which the piston is placed under pressure from the conducting means adapted to retard the closing of the valve, and means for automatically opening and closing said valve, having an element arranged in the path of the car to be cleaned.
- 70 23. In an apparatus for cleansing or cooling the exteriors of cars, the combination with conducting means for the washing or cooling fluid, having a discharge outlet and a valve for controlling the supply of fluid to said outlet, of valve operating means arranged in the path of the car to be cleansed or cooled so as to be operated thereby to open said valve, means for automatically returning said valve to its seat and means for retarding said return so as to thereby obviate the necessity of re-opening the valve for each car of a train.
- 75 24. In an apparatus for cleansing or cooling the exteriors of cars, the combination with conducting means for the cleansing or cooling fluid, having a discharge outlet and a valve for controlling the supply of fluid to said outlet, of a pivoted lever connected with said valve and provided with a means arranged in the path of the car so as to be engaged thereby to adjust said lever to open the valve, and devices for effecting a slow closure of said valve when the car is disengaged from said means.
- 80 25. In an apparatus for cleansing or cooling the exteriors of cars, the combination with conducting means for the washing or cooling fluid, having a discharge outlet and a valve for controlling the supply of fluid to said outlet, said valve having a stem, of a pivoted lever, connections between said lever and valve stem by which bodily movement is imparted to the latter from pivotal movement of the former, a head connected with the lever and arranged in the path of the car to be cleansed, returning devices for said parts, and means for retarding said return, including a chamber through which the valve 85 stem extends, said chamber having provision for slow bleeding, and a piston mounted on said stem and arranged in said chamber.
- 90 26. In an apparatus for cleansing or cooling the exteriors of cars, the combination with conducting means for the washing or cooling fluid, having a discharge outlet and a valve for controlling the supply of fluid to said outlet, said valve having a stem provided with lateral projections, of rods arranged on opposite sides of said stem and having longitudinal openings which receive said projections, levers arranged at the ends of said rods and supporting the same, a link pivoted to one of said levers, and a lever con- 100
- 105 110 115 120 125 130

nected with said link and operated to raise and lower said valve.

27. In an apparatus for cleaning or cooling cars, fluid supply means having discharge pipes provided with apertures arranged to direct the fluid slantingly forward and rearward against the sides of the car.

28. In an apparatus for cleansing or cooling the exteriors of cars, the combination with conducting means for the cleansing or cooling fluid, having a plurality of discharge pipes with their discharge apertures respectively arranged to discharge forward and rearward toward the car, of a valve for controlling the supply of fluid to said pipes, means operated by the car to be cleansed or cooled for opening said valve, returning means for closing the valve, and means for retarding the closing of said valve.

29. In an apparatus for cleansing or cooling the exteriors of cars, the combination with conducting means for the cleansing or cooling fluid, having discharge apertures respectively arranged to discharge forward and rearward toward the car, and means operated by the car for controlling the supply of fluid to said apertures.

30. In an apparatus for cleansing or cooling the exteriors of cars, the combination with conducting means for the cleansing or cooling fluid having apertures which discharge slantingly forward and rearward toward the car, of a valve for controlling the supply of fluid to said apertures, means operated by the car to be cleansed or cooled for opening said valve, and means for effecting a slow closure of said valve when the car has passed out of engagement with said valve-opening means, substantially as described and for the purposes specified.

31. An apparatus for cleansing or cooling the exteriors of cars, having conducting means for the cleansing or cooling fluid provided with discharge slots having their walls extending slantingly and directing the fluid in sheets forward and rearward toward the car body.

32. In an apparatus for cleansing or cooling the exteriors of cars, the combination with conducting means for the cleansing or cooling fluid, having discharge slots directed slantingly forward and rearward toward the car, of a valve, opening means for said valve arranged to be operated by said car, and means for effecting a slow return of the valve.

33. In an apparatus for cleaning or cooling the exterior of a car, conducting means for the cleaning or cooling fluid, having an elongated discharge aperture adapted to discharge the fluid in a sheet slantingly forward toward the car and an elongated discharge aperture adapted to discharge the fluid in a sheet slantingly rearward toward the car.

34. In an apparatus for cleaning or cool-

ing the exterior of a car, conducting means for the cleaning or cooling fluid having elongated discharge apertures adapted to discharge the fluid in sheets forward and rearward toward the car body, and means controlled by the car to be cleaned for controlling the supply of fluid to said apertures.

35. In an apparatus for cleaning or cooling the exterior of a car, conducting means for the cleaning or cooling fluid having elongated discharge apertures adapted to discharge the fluid in sheets forward and rearward toward the car body, a valve controlling the supply of fluid to said apertures and an operating means for said valve adapted to be operated by the car to be cleaned.

36. In an apparatus for cleaning or cooling the exterior of cars, conducting means for the cooling or cleaning fluid, provided with a pipe having a discharge aperture and a valve for controlling the supply of fluid to said aperture; means operated by the car to be cleaned or cooled, for opening said valve; a returning means for the valve; a piston having connection with the valve; and a piston casing having means through which its portion toward which the piston moves in the closing of the valve is supplied with fluid under pressure from the conducting means, and also having means for the restricted outflow of the fluid from its said portion.

37. In an apparatus for cleaning or cooling the exteriors of cars, conducting means for a cleaning or cooling fluid, having apertures adapted to discharge the fluid slantingly forward and rearward toward the car; a valve controlling the supply of fluid to said apertures; means for opening and closing said valve; a piston connected with said valve; and means whereby the piston in the closing of the valve is placed under pressure of fluid from the conducting means in a direction adapted to retard such closure.

38. In an apparatus for cleansing or cooling the exteriors of cars, the combination with means for supplying water under pressure and a discharge pipe provided with a longitudinal discharge opening extending continuously therein and of approximately the same length as the height of the car, a valve for controlling the supply of water to said pipe, means for operating said valve, and means for adjusting the width of said opening.

39. In an apparatus for cleansing or cooling the exteriors of cars, the combination of fluid-supply means having a discharge pipe provided with a longitudinal discharge opening through which the fluid is discharged in a sheet laterally from said pipe, said pipe having transverse slots contiguous to the ends of said opening, and clamping means operated to adjust the width of said opening.

40. In an apparatus for cleansing or cooling cars, the combination of a standpipe,

branch pipes extending on opposite sides of said standpipe and connected therewith and supported thereby and a series of discharge pipes projecting from each branch pipe, said discharge pipes having longitudinal apertures through which the fluid is discharged in sheets.

41. In an apparatus for cleansing or cooling cars, fluid-conducting means, comprising 10 a main supply pipe, a branch supply pipe connected therewith and extending therefrom in the direction of the length of the car to be cleansed or cooled, and a plurality of discharge pipes supported by said branch 15 pipe and projecting therefrom in the direction of the height of the car to be cleansed or cooled and arranged at different places along the length of said pipe and having discharge apertures in their longitudinal walls, the 20 ends of said discharge pipes remote from said branch pipes being free, and a closing device for the free end of each discharge pipe adapted to permit the same to be opened.

42. An apparatus for cleansing or cooling 25 cars, comprising a pipe connected with a source of water supply and provided with means through which water is discharged therefrom against the side of the car, a valve for controlling the supply of water to said pipe, and a lever supported by said pipe and arranged in the path of the car so as to be operated thereby to open said valve.

43. In an apparatus for cleansing or cooling cars, the combination of a standpipe at 35 one side of the track, a pipe leading therefrom to the other side of the track, a valve located in advance of the junction of said pipes, branch pipes connected with said standpipe and pipe respectively, discharge 40 pipes projecting from said branch pipes and having discharge apertures arranged to discharge forward and rearward toward the car, and means for operating said valve.

44. In an apparatus for cleansing or cooling 45 cars, the combination with a standpipe at one side of the track, and a pipe leading therefrom to the other side of the track, of a valve located in advance of the junction of said pipes, branch pipes connected with said 50 standpipe and pipe, respectively, discharge pipes projecting from said branch pipes and having discharge apertures arranged to discharge forward and rearward toward the car, means for opening said valve, and means for 55 causing a slow return of the same for the purpose specified.

45. In an apparatus for cleansing the exteriors of cars, the combination with water-conducting means having discharge pipes 60 provided with elongated longitudinal discharge apertures through the walls thereof for discharging the water in sheets against the side of the car, and a valve controlling the supply of water to said pipes, of means 65 operating on the car in advance of the appli-

cation of water thereto for removing the dust therefrom, and a lever connected with said valve and dust-removing means for operating both of the same.

46. An apparatus for cleansing the exteriors of cars, comprising valve-controlled water-conducting means and valve-controlled means for conducting air under pressure, said means having discharge pipes provided with elongated longitudinal discharge apertures directed toward the car, and a lever connected with said valves for controlling the operation of both of the same, said lever having a head in the path of the car to be cleansed.

47. An apparatus for cleansing the exteriors of cars, comprising a pipe divided into separate chambers, means for conducting water under pressure to one of said chambers and means through which air under pressure is supplied to the other of said chambers and having discharge apertures in their walls, discharge pipes leading from said chambers, separate valves controlling the supply of fluids to said apertures, and a means connected with both of said valves for controlling the operation of the same.

48. An apparatus for cleansing the exteriors of cars, comprising a pipe divided into separate chambers, means for conducting water under pressure to one of said chambers and means through which air under pressure is supplied to the other of said chambers, discharge pipes leading from said chambers and having longitudinal discharge apertures in the walls thereof directed toward the car, valves for controlling the supply of fluids to their respective chambers, and means for automatically controlling the operation of said valves, including a lever having a head in the path of the car to be cleansed and having connections with said valves.

49. An apparatus for cleansing the exteriors of cars, comprising a pipe divided into separate chambers, valved means through which said chambers are supplied with a wet and a dry fluid under pressure, respectively, discharge pipes leading from said chambers, and means operated under the control of the car to be cleansed and provided with devices connecting it with the valves of said wet and dry-fluid supply means.

50. In an apparatus for cleansing or cooling cars, the combination with a discharge pipe a valve which controls the supply of the 110 cleansing or cooling fluid, of an actuating means for said valve provided with a head adjustable into and out of the path of the car to be cleansed or cooled.

51. In an apparatus for cleaning or cooling the exterior of a car, the combination with a fluid conducting means having a discharge outlet and a valve for controlling the supply of fluid to the outlet, means operated by the car for effecting the opening of the 125 130 135

valve and means for closing said valve, the latter adapted to obviate the necessity of re-opening the valve for each car of a train.

52. In an apparatus for cleaning or cooling the exterior of a car, the combination with conducting means for a cleaning or cooling fluid, provided with a discharge outlet and a valve for controlling the supply of fluid to said outlet, of means operated by the car to be cleaned or cooled for opening said valve, means for closing said valve when the operating means is not engaged with the car and means for retarding the closing of the valve, comprising a piston which is connected with said valve and means for placing said piston under pressure from the conducting means in a direction opposite that in which the piston moves in the closing of the valve.

53. In an apparatus for cleaning or cooling the exteriors of cars, the combination with conducting means for the cleaning or cooling fluid, provided with a fluid discharge pipe and a valve for controlling the supply of fluid to said pipe, of means operated by the car to be cleaned or cooled for opening said valve, a returning means for said valve, a piston having connection with said valve and a chamber within which said piston is located, said chamber having means through which it is supplied with fluid and also having provision for slow bleeding.

54. An apparatus for cleansing or cooling cars, including means for discharging fluid against the car, a valve for controlling the supply of fluid thereto, a head adapted to be arranged in the path of the car and connections between said head and valve for actuating the latter when the head is struck by the car, said head being adjustable relatively to said connection so as to be moved into or out of the path of said car.

55. An apparatus for cleansing or cooling cars, including means for discharging fluid against the car, a valve for controlling the supply of fluid thereto, a lever connected

with said valve and a head carried by said lever and adapted to be normally arranged in the path of said car, said head being adjustable relatively to said lever out of the path of the car, and means for holding the head in 50 adjusted position.

56. In an apparatus for cleansing or cooling cars, the combination with a discharge pipe and a valve which controls the supply of the cleansing or cooling fluid, of means for actuating the same, having a head and connections between said head and valve, said head being adjustable relatively to said connections out of and into the path of the car to be cleansed, and means for locking said head in its adjusted positions.

57. In an apparatus for cleansing or cooling cars, the combination with a discharge pipe and a valve which controls the supply of the cleansing or cooling fluid, of means for actuating the same, said means having a lever connected with the valve, said lever having a lateral extension from one end, an arm pivoted at one end to said extension and adjustable relatively thereto and a head carried 70 by the other end of said arm.

58. In an apparatus for cleansing or cooling cars, the combination with a discharge pipe and a valve which controls the supply of the cleansing or cooling fluid, of a lever connected with the valve, said lever having a lateral extension from one end, an arm pivoted at one end to said extension and adjustable relatively thereto, a returning spring connecting said arm with the lever, a head 75 carried by said arm, and means for locking said head and arm in both adjusted positions.

In testimony whereof, I affix my signature, in presence of two witnesses.

HARRISON M. TURNER.
